(57) **CLAIM**

The ornamental design for an enhanced ball round, as shown and described.

DESCRIPTION

FIG. 1 is a front side view of an enhanced ball round according to an embodiment of the invention. The view from the rear side, right side and left side being identical thereto. FIG. 2 is a front side perspective view of the enhanced ball round of FIG. 1. The view from the opposite side being identical thereto.

FIG. 3 is a top view of the enhanced ball round of FIG. 1; and,

FIG. 4 is a cross sectional view of the enhanced ball round of FIG. 1 in order to illustrate clearly the exteriorly exposed shape of the forward portion. Only the exteriorly exposed surfaces are claimed. The internal features are not claimed. The circumferential lines in the drawing represent changes in contour radius and not surface ornamentation.

The bottom view is omitted and forms no part of the claimed design.
